UNITED STATES PATENT OFFICE.

WARREN A. SMITH, OF MARSHALL, MISSOURI.

ANCHORING DEVICE.

Application filed January 18, 1926. Serial No. 82,171.

This invention relates to anchoring devices especially adapted for holding the bottom portions of wire fences close to the ground, an object being to provide a device for this purpose which will successfully resist the efforts of hogs and other animals and prevent them from passing beneath the fence.

Another object of the invention is the provision of an anchoring device which is simple and durable in construction and which is capable of being driven into the ground and spread during the driving operation to provide a secure holding means.

With the above and other objects in view, the invention further includes the following novel features and details of construction, to be hereinafter more fully described, illustrated in the accompanying drawings and pointed out in the appended claim.

20 In the drawings:—

Figure 1 is a perspective view showing a fragmentary portion of a wire fence with the invention applied.

Figure 2 is an enlarged detail perspective view of the anchor.

Referring to the drawings in detail wherein like characters of reference denote corresponding parts, the anchor as shown comprises a member 10 which is preferably 30 formed of bendable metal and is split longitudinally as shown at 11 to provide spaced legs 12.

The outer or free ends of the legs are relatively offset and may be beveled as at 13 so 35 as to provide deflecting means when the anchor is driven into the ground and cause the legs to be further separated. The legs may be also curved in the direction of their lengths to provide the desired offset. In

addition, the side edges of the legs may be 40 beveled as shown at 14 to facilitate their entrance into the ground.

The anchor is placed across the lowermost wire A of the fence and driven into the ground, the curved or offset character of the 45 legs causing the latter to separate in the direction of the length of the wire A and securely hold the anchor in position. If desired, the inner end of the slit 11 may be enlarged as shown at 15 to accommodate the 50 wire A.

The invention is susceptible of various changes in its form, proportions and minor details of construction and the right is herein reserved to make such changes as properly fall within the scope of the appended 55 claim.

Having described the invention what is claimed is:—

An anchoring device of the character described, comprising an elongated flat plate split longitudinally throughout the major portion of its length to provide a pair of legs, and having a circular opening communicating with the inner end of the split, 60 said legs and side edges of the plate being beveled, each leg being beveled longitudinally from a point in its length toward the free end thereof, said legs being spaced in parallelism for a portion of their length, and 65 curved in a direction of their length throughout their remaining length, whereby said legs are crossed at an appropriate point above the free end thereof and adapted to spread outwardly as the anchor is driven into the 70 ground.

In testimony whereof I affix my signature.

WARREN A. SMITH.
